UNITED STATES PATENT OFFICE.

JOHN H. LEYSON, OF BUTTE CITY, MONTANA.

DESIGN FOR A BREASTPIN.

SPECIFICATION forming part of Design No. 22,166, dated January 31, 1893.

Application filed August 16, 1892. Serial No. 443,265. Term of patent 3½ years.

To all whom it may concern:

Be it known that I, JOHN H. LEYSON, a citizen of the United States, residing at Butte city, Silver Bow county, State of Montana, 5 have invented and produced a new and original Design for a Breastpin, of which the following is a description, reference being had to the drawings accompanying, which show, in—

Figure 1 a rear elevation of the design and 10 in Fig. 2 a top plan view thereof.

The leading or characteristic feature of the design comprises a conventional outline representation of the "coat of arms" of the State of Montana having centrally disposed across 15 the back thereof the figure of a nail, the head projecting beyond the body of the pin on the one side and the point projecting beyond the body of the pin on the other side.

A represents a hollow casing upon the back of the pin the outer face of said casing being of crenelated or open-work formation, as shown. 20

B represents the body of the breastpin having the outline of the coat of arms of the State of Montana. 25

C represents the nail seated upon the back of the pin as described.

What I claim is

The design for a breast pin substantially as shown and described. 30

Butte city, Silver Bow county, Montana,
August 11, 1892.

JOHN H. LEYSON.
